UNITED STATES PATENT OFFICE.

WILLIAM DAWSON, OF HAWARDEN, IOWA.

RECIPROCATING PROPELLER.

No. 884,474.

Specification of Letters Patent.

Patented April 14, 1908.

Application filed September 12, 1907. Serial No. 392,545.

To all whom it may concern:

Be it known that I, WILLIAM DAWSON, a citizen of the United States, residing at Hawarden, in the county of Sioux and State 5 of Iowa, have invented certain new and useful Improvements in Reciprocating Propellers; and I do declare the following to be a full, clear, and exact description of the invention, such as will enable others skilled in 10 the art to which it appertains to make and use the same.

This invention relates to improvements in reciprocating propellers for vessels.

The object of the invention is to provide 15 a propeller of this character which will be simple, strong and durable in construction, efficient in operation, and well adapted to the purpose for which it is designed.

With the foregoing and other objects in 20 view, the invention consists of certain novel features of construction, combination and arrangement of parts, as will be more fully described and particularly pointed out in the appended claims.

25 In the accompanying drawings: Figure 1 is a horizontal sectional view of a propeller constructed in accordance with the invention; Fig. 2 is a vertical cross-sectional view of the same; and Fig. 3 is a vertical longitudinal sectional view through one of the propellers casings, showing the arrangement of the propeller therein.

Referring more particularly to the drawings, 1, denotes the propeller casings of 35 which there may be any desired number, said casing being arranged and supported in a suitable position on the vessel and projected longitudinally to the same. In the present instance, I have shown two of the casings arranged side by side, and supported in a frame work, 2, of the vessel. The casings, 1, are preferably rectangular in cross-section and of such length as to provide for the proper movement of the propellers arranged 40 therein.

In each of the casings, 1, is slidably mounted a short inner casing, 3, said casing being also rectangular in cross-section and adapted to slidably engage the inner walls of the outer casing, 1. The casings, 3, are provided on 45 their upper and lower sides with laterally projecting guide studs, 4, which are adapted to engage central longitudinally disposed guide grooves or channels, 5, formed in the upper and lower sides of the outer casing, 1, as shown. The studs working in the chan-

nels, 5, serve to hold the inner casings steady and to cause the same to move evenly when reciprocated in the outer casing, 1.

The casings, 1 and 3, are open at each end 60 and to the inner ends of the casing, 3, are connected the ends of operating rods, 6. The outer ends of which are rigidly connected to cross-heads, 7, which are slidably engaged with guide bars, 8, the inner ends of 65 which are connected to the casings, 1, while their outer ends are suitably connected to the frame work of the vessel. The cross-heads, 7, are provided in their opposite ends with grooves or notches, by means of which 70 they are supported in slidable engagement with the guide bars, 8. The ends of the operating rods, 6, project through the cross-heads, 7, and are adapted to be connected by pitman rods, 9, to a crank shaft, 10, or any 75 other suitable operating mechanism. The cranks on the shaft, 10, are arranged to project in opposite directions so that when one of the propellers is projected forwardly the other propeller will be moved rearwardly, as 80 will be understood.

In each of the inner casings, 3, is arranged one or more series of pivotally mounted wings or blades, 12, said wings being arranged in pairs having their inner ends hing- 85 edly connected to centrally disposed vertical shafts, 13, secured at their upper and lower ends to upper and lower sides of the inner casings, as shown. The wings, 12, are hing- 90 edly mounted on the shafts, 13, in such posi- 95 tion that when the casings, 3, are moved out- 100 wardly on the forward stroke of the operat- 105 ing rods, said wings will fold inwardly into engagement with triangularly shaped stops, 14, arranged on the walls of the top and bot- 110 tom side of the casings, 3, said stops prevent- 115 ing the wings from folding entirely together, so that when the casings, 3, are drawn back on the inward stroke of the operating rods the water will enter between said folded wings, and force the same outwardly until the outer edges thereof are engaged with the opposite side walls of the casing, in which position they serve to propel the vessel for- 120 wardly when drawn back against the water, 125 by means of the operating rods, 6.

Having thus described my invention, what I claim as new and desire to secure by Letters-Patent, is:—

1. A propeller of the character described, 110 comprising a plurality of tubular outer casings, tubular inner casings adapted to fit and

slide in said outer casings, means in the upper and lower sides of said outer casings and on the adjacent sides of said inner casings whereby the latter are guided and steadied in their movements, means to alternately reciprocate said inner casings in the said outer casings, and wings or blades pivotally mounted at their inner ends in said inner casings and adapted to assume an inoperative position on the forward stroke of said inner casings and an operative position on the return stroke of the same, substantially as described.

2. A propeller of the character described comprising a plurality of tubular outer casings having formed in their upper and lower sides longitudinally disposed guide channels, tubular inner casings adapted to fit and slide in said outer casings, guide studs arranged on said inner casings to engage the guide channels in said outer casings whereby said inner casings are guided and steadied in their movement in said outer casings, means to reciprocate said inner casings, pivot shafts arranged therein, wings or blades pivotally mounted on said shafts and adapted to swing inwardly and outwardly to open and close said inner casings when the same are reciprocated and means to prevent said wings from folding entirely together when swung inwardly to open said casings, substantially as described.

3. A propeller of the character described,

comprising a plurality of longitudinally disposed tubular outer casings, a tubular inner casing slidably mounted in each of said outer casings, operating rods connected to the inner ends of said inner casings, cross-heads adapted to slidably support the outer ends of said operating rods, means whereby said operating rods and inner casings are alternately reciprocated in opposite directions, a series of vertically disposed shafts arranged in each of said inner casings, a series of wings or blades arranged in pairs and pivotally connected at their forward ends to said shafts whereby when the inner casings are moved outwardly on the forward stroke, said wings or blades will swing inwardly to a partially folded position, and when moved inwardly on the return stroke will open out against the sides of the inner casing, triangularly shaped stop plates arranged in said casing to prevent said wings folding entirely together, and means arranged on said inner casings, whereby the same are held true and steady in their movement through the outer casing, substantially as described.

In testimony whereof I have hereunto set my hand in presence of two subscribing witnesses.

WILLIAM DAWSON.
